SEWING MACHINE ATTACHMENT

Filed Sept. 15, 1927

Inventor
Horace M. Eaton
by Roberts, Cushman & Woodbury
Attnys.

UNITED STATES PATENT OFFICE

HORACE M. EATON, OF NAHANT, MASSACHUSETTS, ASSIGNOR TO PARCO SPECIALTY COMPANY, OF LYNN, MASSACHUSETTS, A CORPORATION OF MASSACHUSETTS

SEWING MACHINE ATTACHMENT

Application filed September 15, 1927. Serial No. 219,619.

This invention relates to sewing machine attachments and more particularly to that class of attachments which are used in sewing flat braid or tape to the edge of sheet material, for example, a French-cord binding strip which is stitched to one marginal face of a shoe upper, folded about the edge of the same, and adhesively secured to the opposite face thereof.

10. The present invention is particularly applicable to use with flat ribbon or braid of the type, which is more specifically described in Patent No. 1,618,754. This tape has one marginal portion which is sewed to the base 15 sheet or upper and an opposite marginal portion which is coated with a strip of adhesive material that is confined to the region of that margin. This adhesive is covered with a temporary protecting strip which is easily peeled therefrom to permit the braid to be 20 pressed into adhesive engagement with the face of the sheet in order to provide a suitable finish for the same.

When an attachment of this character is 25 utilized in conjunction with partially coated and covered braid of the type disclosed in the above-identified patent, it is essential to take particular precautions against twisting of the braid due to its unsymmetrical form. 30 Accordingly one aspect of the invention relates to the arrangement of an improved form of braid guiding means including a novel form of braid channel which is particularly adapted to cooperate with the type 35 of tape particularly referred to above.

The device is arranged to permit application 40 of braid of this character to curved as well as straight marginal portions of the upper, and also permits the seam to be located very close to the edge of the braid. In order 45 to permit the accurate positioning of the braid guide in relation to the presser-foot these parts are made relatively adjustable in a plurality of directions while the device may also be made adjustable to accommodate braids of various widths.

A further aspect of the invention relates 50 to the arrangement of the various component parts of the sewing machine attachment so that they may be inexpensively manufactured.

and easily adapted to application to a wide variety of sewing machines. The present invention therefore provides a simple, comparatively inexpensive, yet highly efficient braiding attachment, certain aspects of which are generally advantageous in this class of devices and certain features of which are particularly essential and desirable for use in conjunction with partially coated tape of the character identified above.

The above and further objects and advantageous features of the invention will be apparent to those skilled in the art upon a reading of the subjoined description and claims in conjunction with the accompanying drawings in which

Fig. 1 is a side elevational view of the attachment as applied to a sewing machine showing certain related parts of the latter;

Fig. 2 is a similar view of the opposite side of the attachment and related parts;

Fig. 3 is a similar view of the front of the attachment and related parts;

Fig. 4 is a similar view of the attachment;

Fig. 5 is an enlarged section on the line 5—5 of Fig. 2;

Fig. 6 is a perspective of one part of the attachment;

Fig. 7 is an elevational detail view of the inlet end of the braid guiding channel; and

Fig. 8 is a section on line 8—8 of Fig. 2.

A braiding attachment of the type exemplified in the accompanying drawings preferably is secured to the presser-foot bar 1 of the sewing machine, the lower portion of which is shown in Figs. 1 to 4 inclusive. The conventional needle bar is designated by the numeral 2 and carries the usual needle 3. Secured to the bar 1 by any suitable fastening means 6 is the presser-foot support 7 which, in the illustrated embodiment of the invention, extends diagonally downward to the region of the needle point. The lower end of this support carries the rotatable presser-foot 8 which is in the form of a knurled wheel rotatably supported upon the pivot element 9. This wheel is provided with the slightly tapered knurled surface 10, which is adapted to engage the braid adjoining the point of contact of the needle with the same, Figs. 1 and 4.

While I have disclosed herein a rotary presser-foot and one form of presser-foot bracket, it is to be understood that the present invention is not limited to these types of construction; for example, the upper portion of the bracket 7 may be of entirely different form to fit another type of sewing machine having a differently shaped or positioned presser-foot bar, although the lower part of this bracket is preferably standardized in all cases in order to fit the interchangeable or standardized braid guides of the type disclosed herewith. A guide of this type preferably has a supporting member designated 15 generally by the numeral 12 which may be of the form disclosed in Fig. 6. This member has a flat extension 13 arranged in close juxtaposition to the inclined portion of presser-foot 7 and is provided with a flat intermediate 20 portion 14 and with an outstanding extension 16 having the elongate opening 17 at its outer end.

Preferably the braid channel or guideway 20 is secured to the intermediate portion 14 of member 12 by soldering, welding or the like. This braid channel comprises a curved hollow member of substantial rectangular cross section with a comparatively shallow depth, preferably being formed of sheet metal, 25 lapped over as designated by numeral 21, Figs. 7 and 8, to provide the interior of the guideway with a smaller depth at the side adjoining the needle. Preferably the upper end of guideway 20 is notched or cut away, as 30 designated by numeral 22, so that the inlet portion is effectively provided with a step to engage the partially coated braid with the temporary protecting strip applied to a portion of its width. Preferably opening 17 35 upon extension 16 of member 12 is arranged in juxtaposed relation to the inlet shown in guide 20, as shown in Figs. 1 and 2, in order to insure direct movement of the braid into the guide channel.

40 The intermediate portion of the lower end of the guideway is broken away, as designated by the numeral 24, to permit the presser-foot 8 to project between the curved side portions which comprise extensions of the 45 guideway 20.

Means are preferably provided to permit adjustment in the effective width of the guideway or braid channel and at the same time to hold the braid, no matter what its width, 50 against the edge of the channel adjoining needle 3. This adjusting means is particularly disclosed in Fig. 3, and comprises a small lever 40 pivotally secured to the wall of the channel and to the ear 41 which comprises 55 an extension of the body portion of support 12. The outer end of this lever is slotted as designated by numeral 42 in order to permit more ready engagement with a tool. Thus 60 the angular position of member 40 may be 65 conveniently varied by loosening the pivot

screw and by engaging the end of the screw driver in the slot 42 and swinging the lever to the desired angular position. Obviously the inner end of this lever when properly adjusted engages the edge of the ribbon or tape to hold it against the opposite wall of the guideway. The lower wall of channel 20 preferably is cut away as designated by numeral 44 to afford suitable accessibility for the member 40.

70 In order to permit accurate adjustment of the guideway 20 in relation to path of needle 3 the extension 13 is adjustably mounted upon bracket 7. Preferably the member 12 and consequently the guide 20 is adjustable laterally as well as backward and forward in relation to the bracket and the presser-foot. For this purpose, I provide an opening 30 in the upper end of extension 13 of the sheet metal member 12 and provide an elongate 75 slot 31 below the opening 30. A suitable fastening element 32, such as a screw, extends through the opening 30 and is threaded into member 7; this element forms a fixed fastening about which the remainder of the member 12 may be swung either in a backward and forward or in a lateral path in order accurately to adjust the same. A hollow screw 35 is threaded into the member 7 and an inner screw 36 is threaded into the 80 interior of the screw 35. Screw 35 is provided with a slot 37 in order to permit its adjustment while screw 36 extends through the slot 31 and is provided with a washer 38 to engage the adjoining portion of member 12. Thus loosening of screw 36 permits the 85 swinging of member 12 about screw 32 as a pivot and permits angular adjustment of the guide in relation to the path of the needle, thus avoiding the necessity of filing the 90 end of the guideway in order to insure the accurate holding of the braid in proper position for stitching. Obviously inward and outward adjustment of the hollow screw 35 95 serves to effect the lateral movement of member 12 in relation to member 7, the degree of adjustment permitted by this means being desirably comparatively fine so that the resilience of extension 13 between fastenings 100 32 and 35-36 permits the minute lateral 105 movement of support 12 in relation to the bracket.

110 In the operation of the device the presser-foot 8 is caused to rest upon the work and the braid is fed through opening 17 and guide 20 to the lowermost portion of the presser-foot which serves to press the braid against the base sheet in close juxtaposition to the 115 path of needle movement. Obviously the 120 adjustable mounting of member 20 permits the braid accurately to be positioned so that the seam is located at the desired distance from the margin of the braid and so that the 125 guideway is brought into the closest practical relation to the path of the needle. The 130

stepped arrangement of the inlet is particularly advantageous when used in conjunction with partially coated tape having a temporary protecting strip for the coated portion such as is described above, since this arrangement of the guideway prevents the tape from twisting due to its unsymmetrical formation, thus avoiding one of the outstanding difficulties which has accompanied the use of this braid in braiders heretofore known to the art. Furthermore, the arrangement of the extension 16 with the guide opening 17 in relation to the stepped inlet end of the guide channel affords a slight drag or light frictional engagement of the moving braid with the braid guiding device, so that too rapid or uneven movement of the tape or braid is avoided, and so that the tape is applied evenly and uniformly to the base sheet or shoe upper.

I claim:

1. An attachment for sewing machines comprising a support portion adapted to be secured to a presser-foot bar, a guide channel for braid supported by said portion, said channel being inclined upwardly and having the upper end of one of its walls provided with parallel edge portions to afford a stepped inlet.
2. An attachment for sewing machines comprising a portion adapted to be secured to a presser-foot bar, a sheet metal member adjustably secured thereto, said member having an extension with an elongate opening to provide a braid guide, and a sheet metal channel secured to an intermediate part of said sheet metal member and disposed to receive braid from said guide.
3. An attachment for sewing machines comprising a portion adapted to be secured to a presser-foot bar, a sheet metal member adjustably secured thereto, said member having an extension with an elongate opening to provide a braid guide, and a channel secured to an intermediate part of said sheet metal member, said channel having a portion adjoining one side of decreased depth in order properly to engage a ribbon having part of its width adhesively coated and protected with a temporary covering strip.

4. An attachment for sewing machines comprising a portion adapted to be secured to a presser-foot bar, a supporting member adjustably secured thereto, said member having an extension with an elongate opening to provide a braid guide, and a channel secured to another part of said supporting member, the latter being adjustable laterally in relation to said presser-foot bar to vary the position of braid fed through the channel in relation to the needle.

5. An attachment for sewing machines comprising a portion adapted to be secured to a presser-foot bar, a supporting member adjustably secured thereto, said member having

an extension with an elongate opening to provide a braid guide, and secured to another part of said supporting member, the latter being adjustable laterally in relation to said presser-foot bar to vary the position of braid fed through the channel in relation to the needle, said supporting member also being adjustable forward and backward in relation to the presser-foot bar to vary the position of the channel in relation to the needle of the sewing machine.

6. An attachment for sewing machines comprising a part to be secured to a presser-foot bar, a presser-foot carried by said part, a braid-receiving channel, a supporting member adjoining said part and supporting said channel, said member and said part being connected by fastening means which permits lateral and angular adjustment therebetween, the said fastening means serving to clamp the part and support member against lateral movement as well as retaining the members against relative movement forward and backward.

7. An attachment for sewing machines comprising a part to be secured to a presser-foot bar, a presser-foot carried by said part, a braid-receiving channel, a supporting member adjoining said part and supporting said channel, said member and said part being connected by fastening means to permit adjustment therebetween in a plurality of directions, said fastening means clamping the part and support member against lateral movement and also retaining the members against relative movement forward and backward, said fastening means comprising a hollow element threaded into said part and a second screw-threaded element engaging the interior of the hollow element and passing through a slot in the supporting member.

8. An attachment for sewing machines comprising a part to be secured to a presser-foot bar, a rotary presser-foot carried by said part, a braid-receiving channel, said channel being curved and having a portion broken away to receive the rotary presser-foot, a supporting member adjoining said part and supporting said channel, said member and said part being relatively adjustable in a plurality of directions, a single fastening means therebetween to be loosened to permit relative adjustment between the part and supporting member in a plurality of directions.

9. An attachment for sewing machines comprising a part to be secured to a presser-foot bar, a presser-foot carried by said part, a braid-receiving channel, said channel being curved and having a portion broken away to receive the presser-foot, a swinging lever member extending into said channel and movable to a plurality of positions to vary the effective width of the channel, a pivot supporting said lever, a portion of the channel wall being cut away to afford convenient ac-

cessibility to the pivot, said pivot being adapted to be loosened to permit movement of the lever and to be tightened to hold the lever in a determined position.

10. An attachment for sewing machines comprising a part to be secured to a presser-foot bar, a rotary presser-foot carried by said part, a channeled braid-receiving member, said member and said part being connected to permit their relative adjustment in a forward and backward direction.

11. An attachment for sewing machines comprising a support portion adapted to be secured to a presser-foot bar, a guide channel for braid supported by said portion, said channel being generally rectangular and comparatively wide and shallow in cross-sections, the channel having upper and lower wall portions, one of said wall portions being provided with planar surfaces in parallel planes, thus providing the channel with a greater depth adjoining one side than adjoining the opposite side, whereby partially coated and covered braid may pass through the channel without tending to twist.

12. An attachment for sewing machines comprising a portion adapted to be secured to a presser-foot bar, a tape guide secured to said portion, said guide comprising sheet metal bent to define a passageway of generally rectangular cross-section, one edge of the sheet metal being lapped over another portion thereof to provide the passageway with less depth at the side where the metal is overlapped than at the opposite side, the wall portions of that part of the passageway which has less depth than the remainder, being substantially planar and in parallelism to the wall portions of the remainder of the channel.

40. Signed by me at Lynn, Massachusetts, this thirteenth day of September, 1927.
HORACE M. EATON.
